GOLF TEE

Fred C. Penny, Avalon, Calif., assignor of one-half to Harry D. Diffin, Avalon, Calif.

Application July 29, 1932, Serial No. 626,120

6 Claims. (Cl. 273—33)

My invention relates to improvements in golf tees, and an important object of the invention is to provide a golf tee which will remain in place in the ground as the ball is struck therefrom, and 5 which will not injure soft wooden headed clubs.

Other objects and advantages of my invention will be apparent from a reading of the following description in connection with the drawing, wherein for purposes of illustration I have shown 10 preferred embodiments of my invention.

In the drawing:—

Figure 1 is a general front elevational view of one form of the invention.

Figure 2 is a back view of Figure 1.

15 Figure 3 is a view taken at right angles to Figure 1.

Figure 4 is a horizontal sectional view taken approximately on the line 4—4 through the middle of Figure 1.

20 Figure 5 is a similar horizontal sectional view taken through the lower part of Figure 1 approximately on the line 5—5.

Figure 6 is a front elevational view of a different form of the invention.

25 Figure 7 is a back view of Figure 6.

Figure 8 is a view taken at right angles to Figure 6.

Figure 9 is a horizontal sectional view taken approximately on the line 9—9 through the 30 lower part of Figure 8.

Figure 10 is a back elevational view of a still further embodiment of the invention.

Figure 11 is a front elevational view thereof.

35 Figure 12 is a view taken at right angles to Figure 11.

Figure 13 is a horizontal sectional view taken through the lower part of Figure 12 taken approximately on the line 13—13.

40 Referring in detail to the drawing, wherein like numerals refer to like parts throughout the same, the illustrated forms of the invention are individually designated by the letters A, B, and C, respectively.

The embodiment or form A comprises a goblet-shaped head 5 having a cupped golf ball receiving depression 6 in its top, and from the goblet-shaped head depends a round tapering shank 7 provided on its front side with angulated flat side portions which define a knife edge 8 extending 45 the full length of the shank almost to the top of the goblet formation 5, the said edge being arranged to cut forwardly into the ground in the same direction as the ball is propelled when the ball and the back of the tee are struck by the club in driving the ball. The upper part of the

back of the shank 7 is smoothed and rounded as indicated at 9 for quite a distance below the head 5, that is, to a point below the middle of the shank, as indicated at 10. The lower part of the back has a short knife edge 11. The different cross sections at vertically spaced points of the shank 7 will be understood by consulting Figures 4 and 5. It is to be observed that the rounded back 9 is presented to the club head as the drive is made, so that neither the club head, such as a 10 soft wooden head, nor the tee is injured by the impact. Because of the forward position of the knife edge 8 and the position of the knife edge 11 at the back of the tee, forward tilting movement of the tee as the ball is struck will cause the upper 15 part of the tee to dig forwardly and the lower part of the back of the tee rearwardly into the ground so that the tee takes a new purchase in the ground instead of flying from the ground and becoming lost. 20

Comparing embodiments A and B it will be noted that the front and back views thereof show the goblet-shaped part, while the views taken at right angles to the front and back views, do not disclose the bulged sides on the head, but show 25 only the tapered form of the head. In embodiment B shown in Figures 6 and 7 and which does not have the bulging sides on the head, the designating numerals are arranged to correspond with the designating numerals in the embodiment A 30 described above, but in the showing of the embodiment B there is added to each designating numeral the distinguishing letter b.

In the embodiment B there is provided instead of the knife edge 12 a rounded groove in the back 35 of the shank which extends from a point 14 near the middle of the shank to and through the lower end of the shank, as indicated at 13. It is to be observed in Figure 8 that the sides of the groove are as a result of the grooving, slightly cusped inwardly as indicated at 14b and sharp. In the front view shown in Figure 7, the knife edge 8b is present as it is in the form or embodiment A and performs the same functions. It will be obvious that as the upper part of the tee in the embodiment B is struck in driving a ball, the tee tilts forwardly whereby the knife edge 8b will be forced forwardly into the ground, while the sharp edges 14b defined by the groove 12 will be caused to cut into the ground in an opposite direction 40 whereby a new purchase in the ground is taken by the tee, which holds the tee from flying from the ground. 50

In the embodiment C shown in Figures 10 to 55 13, inclusive, the forward knife edge 8c is like

the knife edges 8 and 8b of the embodiments A and B, and the head 5b is similar to the head 5 in embodiment A, but instead of having a short knife edge on the back reaching from the point 5 10c to the lower end of the shank, the embodiment C has simply a narrow flattened portion 15 which acts rearwardly against the earth as the tee is thrown forwardly when struck. The width of the narrow flat portion 15 is defined by the 10 sides which form the front knife edge. These sides are more acutely angulated and extend farther toward the back of the shank than the corresponding sides in the embodiments A and B, as will be evident in Figure 12.

15 It will be observed that in all forms or embodiments of the invention, the arrangement of securing a plurality of the tees in a "stick" may be practiced, so that the user will be protected against the injury and inconvenience which accompanies carrying about several of the tees loosely in the pockets. The material for making the tees is preferably celluloid or similar materials in public favor. Ease of accurate application to the ground is common to all forms of the 20 invention, and as before stated, the contours and features of the tees of the invention prevent injury to soft wooden club heads, and prevent loss and defacing of the tees from being struck in the act of driving.

30 Although I have shown and described herein preferred embodiments of my invention, it is to be definitely understood that I do not desire to limit the application of the invention thereto, and any change or changes may be made in material and structure and arrangement of parts, within the spirit of the invention and the scope 35 of the subjoined claims.

What I claim as new is:—

1. A golf tee comprising a globular head for 40 supporting a ball, a tapered shank depending from said head, a knife edge extending along the front of the shank and head, a groove extending only along a lower part of the back side of the shank and defining a pair of ground engagings rearwardly directed sharp edges.

2. A golf tee consisting of a conical body having a ball receiving depression in its larger and upper end, the front of said body having a knife edge extending substantially the full height of 50 the body and arranged to cut forwardly into the ground when the upper part of the back of the tee is struck and the tee is tilted forwardly in driving a ball from the tee, the lower part of the back of the body having a vertical sharpened 55 portion extending downwardly from a point intermediate the upper and lower ends of said body to the lower end thereof, said vertical sharpened portion being arranged to cut sufficiently rearwardly into the ground when the upper part of the tee is tilted forwardly by the impact to prevent breaking of the tee and dislodgment thereof from the ground by the impact, the portion of the back of the body above the upper end of said vertical sharpened portion having the full 60 contour of the upper part of the body so as to present a broad impact receiving surface, said vertical sharpened portion consisting of a pair of rearwardly directed substantially parallelly spaced sharp edges.

70 3. A golf tee consisting of a conical body having a ball receiving depression in its larger and upper end, the front of said body having pro-

jecting forwardly therefrom a knife edge extending substantially the full height of the body in position to cut forwardly into the ground when the upper part of the back of the tee is struck in driving a ball from the tee, the lower part 5 of the back of the body having a vertical sharpened portion extending downwardly from a point intermediate the upper and lower ends of said body to the lower end thereof, said vertical sharpened portion being arranged to cut sufficiently rearwardly into the ground when the upper part of the tee is tilted forwardly by the impact to prevent breaking of the tee and dislodgment thereof from the ground by the impact, the back of the body above the upper end of said vertical 15 sharpened portion having the full contour of the upper part of the body so as to present a broad impact receiving surface, said vertical sharpened portion comprising a pair of spaced sharp edges, the lower part of the back of the body between 20 said pair of sharp edges being formed with a vertical groove providing a chamber normally partly empty to accommodate more ground substance as the tee is tilted forwardly so that the rearward movement of said sharp edges into the 25 ground is facilitated.

4. A golf tee comprising a conical body having a ball seating depression in its large and upper end, opposite side portions of the forward face of said body being flattened and angularly disposed to provide a sharp edge extending from the lower end of the body to a point near the top of the body, a short groove in the opposite and rear face of said body and running from a point spaced below the upper end of the body 35 to the lower end of the body and defining a pair of relatively sharp rearwardly directed edges.

5. A golf tee comprising a conical body having a ball seating depression in its large and upper end, opposite side portions of the forward face 40 of said body being flattened and angularly disposed to provide a sharp edge extending from the lower end of the body to a point near the top of the body, a short groove in the opposite and rear face of said body and running from a point spaced below the upper end of the body to the lower end of the body and defining a pair of relatively sharp edges, said groove being substantially semicircular in cross section.

6. A golf tee comprising a large cup-shaped head, a relatively small shank depending from said head, said shank being of substantially circular cross section and tapering uniformly from its top to its bottom, a vertically disposed wedge-shaped edge on and projecting radially outwardly 55 from the front of said shank and extending from the lower end of the shank to a point near the top of said head, said edge being arranged to cut forwardly into the ground when the upper part of the back of the tee is struck in driving a ball 60 from the tee, and a pair of wedge-shaped projections on the lower part of the back of said shank for cutting rearwardly into the ground as the tee is tilted, said projections extending from the lower end of the shank to a point spaced below the upper end of the back of the shank, the lower part of the back of the shank being formed with a groove lying between and coextensive with said wedge-shaped projections, the back of the shank above the upper ends of said projections and said 65 groove being unencumbered so as to present a broad rounded impact surface.

FRED C. PENNY.
